(57) **CLAIM**

The ornamental design for the guitar, as shown and described.

DESCRIPTION

FIG. 1 is a perspective view of the guitar showing my new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof;

FIG. 7 is a bottom plan view thereof;

FIG. 8 is a magnified view of the octagonal pattern and octagonal resonance hole; and,

FIG. 9 is a magnified view of the round-type edge of the upper right body.

The details shown in broken lines in all views are for illustrative purposes only and form no part of the claimed design.
